UNITED STATES PATENT OFFICE.

CHARLES F. CHANDLER, OF NEWARK, NEW JERSEY.

STEAM-ENGINE.

SPECIFICATION forming part of Letters Patent No. 357,655, dated February 15, 1887.

Application filed March 17, 1886. Serial No. 195,532. (No model.)

To all whom it may concern:

Be it known that I, CHARLES F. CHANDLER, of Newark, in the county of Essex and State of New Jersey, have invented a new and Improved Steam-Engine, of which the following is a full, clear, and exact description.

The object of my invention is to provide a new and improved steam-engine in which the pressure of the steam is completely utilized, and the power derived from the steam is equally applied to the crank-shaft in such a manner as to avoid dead-centers.

The invention consists of a steam-cylinder having two pistons which advance toward or recede from each other; of a rotary valve in the steam-chest; of pitmen connected with crank-arms placed at angles to each other on the main shaft, and of a reversing-gear for the rotary valve.

20 The invention also consists of various parts and details, and combinations of the same, as will be fully described hereinafter, and then pointed out in the claims.

Reference is to be had to the accompanying drawings, forming a part of this specification, in which similar letters of reference indicate corresponding parts in all the figures.

Figure 1 is a plan view of my improvement. Fig. 2 is a longitudinal sectional elevation of 30 the same on the line $x-x$, Fig. 1. Fig. 3 is a top view of the valve-seat; and Fig. 4 is a bottom view of the rotary valve.

The steam-engine is mounted on a bed-plate, A, of suitable construction, and provided with 35 the cylinder B, having two pistons, C and D, of which the piston C has a piston-rod, E, connected with a cross-head, F, sliding in suitable bearings and connected with the crank-arm G' on the main shaft G by the pitman H. 40 The piston D is provided with a piston-rod, I, on the outer end of which is secured a cross-head, J, sliding in suitable bearings, J', and having each end J' connected with a crank-arm, G'', attached to the main shaft G by the 45 rods or connecting-arms K. The crank-arm G' is set in such a position in relation to the crank-arm G'' that when one is in a dead-center position the other stands at an angle to the same.

50 The cylinder B is provided with the port-hole a, which opens at its ends into the re-

spective ends of the cylinder, and connects with the valve-seat by means of the opening b, and with a port, c, which leads from the center of the cylinder to the valve-seat L. The 55 exhaust-port d connects with the seat L and leads to the exhaust-pipe M.

The steam-chest N is fastened to the cylinder B, and is provided with the usual steam-inlet, N'. In the steam-chest N operates the 60 rotary valve O, having a wedge-shaped aperture, O', and a recess, O''. The rotary valve O is provided with a vertical valve-stem, O³, which passes through a suitable stuffing-box in the steam-chest N, and is provided on its 65 outer end with the arm P, which connects by a link, Q, with the rocking arm R, pivoted at its lower end to the bed-plate A.

The eccentric S, mounted on the main shaft G, is provided with the eccentric-rod T, having a handle, T', and a notch, T'', which engages with a pin, R', on the rocking arm R. The eccentric-rod T can be locked in place on the pin R' by means of the arm U, pivoted to the rocking arm R, which is also provided 75 with a handle, R''.

The operation is as follows: The rotary valve O is so arranged that when its aperture O' is over the opening b of the port a steam is admitted to both ends of the cylinder B, and at 80 the same time the other port, c, connects, by means of the cavity O'', with the exhaust-port d, and when the opening O' is over the port c steam is admitted to the center of the cylinder B, and the port b is connected with the exhaust-port d by means of the cavity O³ in the rotary valve O. As shown in the drawings in Fig. 2, the pistons C and D are in their innermost position, and steam being admitted to the cylinder B by means of the port c and the 85 rotary valve O, as above described, the pistons C and D will recede from each other and impart motion by means of their piston-rods to their respective cross-heads, which in turn actuate the crank-arms on the main shaft G by 90 means of the pitman H and the connecting-rods K. Before the pistons C and D have reached the end of their outward stroke the rotary valve will close the port c and open the port b, so as to admit steam to the ends of the 95 cylinder. This movement of the valve O is derived from the main shaft G by the eccen-

tric S and its arm T, imparting a rocking motion to the arm R, which in turn, by means of the link Q and the arm P, turns the valve O. The motion of the pistons C and D will be 5 reversed by the steam entering through the port a, so as to force the pistons C and D toward each other. The exhaust takes place through the port c into the cavity O², and out through the exhaust-port d, when the pistons 10 are traveling toward each other, and when the pistons are receding from each other the exhaust takes place by the port a, its opening b, the cavity O², and the exhaust d, as before described.

15 The engine can be run by hand when necessary—as, for instance, when it stands on centers—by disengaging the arm U from the eccentric-arm T, and lifting the eccentric-rod upward by means of the handle T', so as to 20 disengage the notch T' from the pin R' of the rocking arm R, and by taking hold of the handle R' on the rocking arm R the rotary valve O can be thrown in such a position that the opening O' will come directly over the 25 port b, or over the port c, as the case may be. The eccentric-arm T is then again engaged with the pin R' on the rocking arm R and locked in place by the arm U.

Having thus fully described my invention, 30 I claim as new and desire to secure by Letters Patent—

1. In a steam-engine, the combination of a cylinder provided with a port opening at the ends of the cylinder, a port opening at the 35 center of the cylinder, and an exhaust-port, and two pistons operating in the said cylinder and actuating the main shaft by suitable connections, with an eccentric placed on the said main shaft and operating a rocking arm, and 40 an oscillating valve having an aperture and a recess in its bottom and suitably connected with the rocking arm operated by the eccentric, substantially as shown and described.

2. In a steam-engine, the combination of a 45 steam-cylinder provided with inlet and outlet ports, and an oscillating valve connected by suitable links to a rocking arm pivoted on the

bed-plate of the engine, with an eccentric placed on the main shaft of the engine and provided with an eccentric-rod, which can be 50 detached from the rocking arm or locked in position on the same by a pivoted arm, substantially as shown and described.

3. In a steam-engine, the cylinder B, provided with a port, a, leading to the ends of the cylinder and opening into the valve-seat L by means of the opening b, the port c, leading to the center of the cylinder, and the exhaust-port d, leading to the exhaust-pipe M, in combination with the pistons C and D, operating the cranks G' and G² on the main shaft G by suitable connections, and the oscillating valve having the aperture O' and the recess O², and operated from the main shaft G by the eccentric S, having an eccentric-rod, T, connected with the rocking arm R, connected to the arm P of the stem O³ of the valve O by the link Q, substantially as shown and described.

4. In a steam-engine, the cylinder B, having 70 the ports a, c, and d, the pistons C and D, operating the main shaft G by suitable connections, and the oscillating valve O, having the aperture O' and the recess O², in combination with the rocking arm R, pivoted to the bed-plate and connected, by means of the link Q, to the arm P of the valve-stem O³, substantially as shown and described.

5. In a steam-engine, the cylinder B, having 80 the ports a, c, and d, the pistons C and D, operating the main shaft G by suitable connections, and the oscillating valve O, having the aperture O' and the recess O², in combination with the eccentric S, the eccentric-rod T, having a handle, T', and a notch, T', the rocking arm R, having the pin R', the handle R', and the rocking arm U, and the link Q, attached to the arm P of the valve-stem O³, substantially as described.

CHARLES F. CHANDLER.
